WALL SWITCH COVER PLATE

George A. Abraham, 7902 Brinsmade St.,
Cleveland, Ohio

Filed June 29, 1959, Ser. No. 56,585

Term of patent 14 years

(Cl. D26—13)

Fig. 2

Fig. 1

Fig. 3

Fig. 4

Fig. 5

Fig. 1 is a front view of the wall switch cover plate embodying my design;

Fig. 2 is a top view;

Fig. 3 is a side view;

Fig. 4 is a bottom view; and

Fig. 5 is a perspective view.

The diagonally lined portion of the plate is a transparency.

I claim:

The ornamental design for a wall switch cover plate, as shown and described.
